BATHROOM LAVATORY UNIT

Bruno Verlet, 1 Rue Jean-Paul Delcourt,
64150 Mourenx, France

Filed Jan. 4, 1974, Ser. No. 430,738

Claims priority, application France Sept. 24, 1973

Term of patent 14 years

Int. Cl. D23—02

U.S. Cl. D23—49

FIG. 1

FIG. 2

FIG. 3

FIG. 4

FIG. 1 is a front elevational view of a bathroom lavatory unit showing my new design;

FIG. 2 is a right side elevational view thereof;

FIG. 3 is a top plan view thereof; and

FIG. 4 is a bottom plan view thereof.

The broken line representation of a faucet fixture in FIGS. 1 and 2 is for purposes of illustration only.

I claim:

The ornamental design for a bathroom lavatory unit, as shown and described.
